UNITED STATES PATENT OFFICE.

OLIVER S. RIGGS, OF ALLENPORT, PENNSYLVANIA.

CAR-COUPING.

SPECIFICATION forming part of Letters Patent No. 247,949, dated October 4, 1881.

Application filed July 9, 1881. (No model.)

To all whom it may concern:

Be it known that I, OLIVER S. RIGGS, of Allenport, in the county of Washington and State of Pennsylvania, have invented a new and Improved Car-Coupler, of which the following is a full, clear, and exact specification.

This invention relates to that class of couplers called "self-couplers;" and it consists of a flaring-mouthed draw-head containing a pivoted drop-catch for engaging the coupling-link, held down by rod and spring and raised by lever, and containing, also, a curved plate rigidly secured in rear of the drop-catch for guiding the coupling-link and holding down its engaged end.

Figure 1 is a sectional side elevation of the coupler. Fig. 2 is a plan of the same on line $\alpha\alpha$, Fig. 1. Fig. 3 is a plan of the coupling-link.

Similar letters of reference indicate corresponding parts.

In the drawings, A represents the draw-head, having a flaring mouth, as shown at a , to facilitate the entrance of a coupling-link and the coupling of high with low cars. Transversely through the upper part of said draw-head A is passed a pin or rod, b, on which is pivoted the swinging elbow-catch B, whose depending end c is narrow enough to enter the coupling-link G, and extends rearward, resting upon the bottom of said draw-head A.

Through a slot, d, in the top of the draw-head A a rod, C, extends downward and has its lower end secured in the prolonged end e of the catch B, and about this rod C is a spiral spring, D, that, pressing between the top of the draw-head A and the catch B, holds the latter down in place.

Pivoted in the top of the draw-head A, on a transverse rod, f, is an elbow-lever, E, in whose horizontal end is a slot, g, up through which the rod C extends, and in which it is held by a pin, h. By means of this lever E the catch

B is raised for the uncoupling of the cars, and a rod may be connected with this lever E and 45 extended forward to within reach of the engineer, by means of which he can uncouple at will while the cars are in motion.

Within the draw-head A, in the rear and bottom thereof, is secured a little above the 50 bottom an upward-curving plate, F, that inclines the entering link G downward and holds it down when entered, as shown, bearing against the end of the catch B. The link G is a flat bar slotted at each end, as shown at $m m$, to receive 55 the ends of catches B, and made narrow in the middle to reduce its weight.

With this coupler, which is simple, strong, and durable, cars can be coupled and uncoupled without going between the cars, and thus the 60 dangers to life and limb incident upon the usual method of coupling and uncoupling may be avoided.

Having thus described my invention, I claim as new and desire to secure by Letters Patent— 65

1. A car-coupler, constructed substantially as herein shown and described, consisting of flaring-mouthed draw-head A, pivoted elbow-drop catch B, rod, spring, and lever C D E, and fixed curved plate F, arranged as set forth. 70

2. In a car-coupler, the combination, with the drop-catch B, of the rod C and lever-elbow E, in whose horizontal end is a slot, g, in which said rod is loosely secured, substantially as herein shown and described, whereby said catch 75 is raised for uncoupling, as set forth.

3. In a car-coupler, the combination, with the drop-catch B, of the curved plate F, substantially as herein shown and described, whereby the coupling-link is guided and held down, as 80 set forth.

OLIVER SANSUM RIGGS.
